DESIGN FOR A STORE SERVICE TRUCK

Arthur Bartel, United States Army,
Comfort, Tex.

Application November 25, 1944, Serial No. 116,552

Term of patent 14 years

(Cl. D14—3)

To all whom it may concern:

Be it known that I, Arthur Bartel, United States Army, a citizen of the United States, residing at Comfort, Texas, have invented a new, original, and ornamental Design for a Store Service Truck, of which the following is a specification, reference being had to the accompanying drawing, forming a part thereof.

I claim:

The ornamental design for a store service truck, as shown.

ARTHUR BARTEL.
